Des. no. 20,190

UNITED STATES PATENT OFFICE.

HENRY CLAY BASCOM, OF LANSINGBURG, AND FRANCIS RITCHIE, OF TROY,
NEW YORK.

DESIGN FOR A HEATING-STOVE.

SPECIFICATION forming part of Design No. 20,190, dated October 7, 1890.

Application filed September 8, 1890. Serial No. 364,351. Term of patent 3½ years.

To all whom it may concern:

Be it known that we, HENRY CLAY BASCOM and FRANCIS RITCHIE, citizens of the United States, residing in the said BASCOM at the village of Lansingburg, county of Rensselaer, and State of New York, and the said RITCHIE at the city of Troy, in said State and county, have invented and produced a new and original Design for Heating-Stoves, of which the following is a specification, reference being had to the accompanying drawing, forming a part thereof and consisting of a single figure, affording a view in perspective of our newly-designed stove.

15 The leading feature of our new design consists of the ornamentation of the various parts of the stove.

The base A is provided with a plain horizontal border-band A', extending to the lower edge of the base and with a continuous bead or pearl border-line A² along its upper edge. The combustion-chamber B rises from the base and is provided on its front with two doors B' and B², one above the other, each of which has a central flambeau ornament B³ and foliated scrolls B⁴, extending one from each side of the torch across the mica openings. On either side of the doors is a vertical panel B⁵, having a foliated ornament thereon, consisting of a flambeau B⁶, supported by a vase B⁷, and conventionalized leafage B⁸. The legs E have their upper ends formed of open scroll-work, the openings E' passing through the right and left wings E² of the leg. The main scrolls E³ on each wing are centrally connected by the horizontal band E⁴. The lower end of each leg or foot is decorated with a foliated scroll E⁵. Projecting from the upper part of the combustion-chamber is a flange provided with the plain border-band C, with the pearl border-line C' along its upper edge. A plain border-band D extends around the lower part of the dome D', the upper part of the dome

being ornamented by the open foliated scroll-work D².

What we claim as new is—

1. The ornamental design for a heating-stove, herein shown and described, consisting of a base having a plain border-band extending to its lower edge and a pearl border-band along its upper edge, a combustion-chamber mounted upon such base and having vertical side panels with a flambeau and flambeau-supporting vase ornament, a door on the front of such combustion-chamber having a flambeau ornament with foliated scrolls branching therefrom, a dome surrounding such combustion-chamber, provided with a plain border-band extending to its lower edge, having its upper portion ornamented by open foliated scroll-work, and a flange at the junction of such combustion-chamber and dome, having a plain border-band with an upper pearl border-line.

2. In a design for a heating-stove, the design on the front of the combustion-chamber, herein shown and described, consisting of two doors, one above the other, provided with flambeau ornaments having foliated scrolls branching therefrom, and a vertical panel on either side of such doors, having thereon a flambeau and flambeau-supporting vase ornament.

3. In a design for a heating-stove, the design for a leg, herein shown and described, consisting of open scroll-work on the upper right and left wings of the leg, a horizontal band centrally connecting the two wing-scrolls, and a foliated scroll upon the foot of the leg.

In testimony whereof we have hereunto set our hands this 6th day of September, 1890.

H. CLAY BASCOM.
FRANCIS RITCHIE.
